CONTAINER

James E. Annen, Kalamazoo, Mich.

Application August 13, 1938, Serial No. 224,701

9 Claims. (Cl. 229—5.7)

This invention relates to improvements in containers.

The main objects of this invention are:

First, to provide a shipping or delivery container for handling various products which can be shipped in the knockdown or disassembled and quickly set up by the user.

Second, to provide a shipping container having walls of fibrous material such as container board which is very strong and secure when set up.

Third, to provide a structure having these advantages which is very economical in its parts.

Objects pertaining to details and economies of my invention will definitely appear from the description to follow. The invention is defined in the claims.

A container embodying the features of my invention is clearly illustrated in the accompanying drawings, in which:

Fig. 1 is a perspective view of a cylindrical container embodying the features of my invention with the cover thereon.

Fig. 2 is an enlarged fragmentary vertical section.

Fig. 3 is a fragmentary vertical section illustrating the manner of assembling the side walls with the bottom.

Fig. 4 is a fragmentary sectional view showing a step in assembling preceding that shown in Fig. 3.

Fig. 5 is a fragmentary longitudinal section of the side wall of my container.

Fig. 6 is a fragmentary vertical section of a modified form or embodiment of my invention.

Fig. 7 is a fragmentary view partially in longitudinal section of a modified form or embodiment of my invention in a container having telescoping side walls whereby the capacity of the container may be varied or the container collapsed as its contents are removed.

Fig. 8 is a bottom plan view of a modified embodiment of my invention.

Fig. 9 is a fragmentary sectional view on line 9—9 of Fig. 8, further illustrating the modified form.

Fig. 10 is a fragmentary view in section similar to Fig. 9, illustrating modified cover provisions suitable for the container of my invention.

Referring to the drawings, the side wall 1 of the embodiments of my invention illustrated is formed of fibreboard or container board and is adapted to collapse, being longitudinally scored at 2 to facilitate collapsing. I have not shown the side wall in collapsed position as this feature will be readily understood.

The side wall is provided at its ends with external hoop-like reinforce members 3 and 4, the members being secured to the side wall by means of adhesive as shown at 5 in Fig. 5. The upper edge of the member 3 provides a ledge 6 for retaining the rim 7, one of the purposes of the reinforce member 3 being to provide this ledge. The end member 8, in this instance the bottom of the container, is provided with an upwardly facing annular side receiving channel 9, the outer wall of which is in the form of a flange 10 embracing the reinforce member 3. This annular channel is of such width at the bottom as to receive the side wall with its reinforcing member 3, see Fig. 2, with the reinforcing member in supporting engagement with the flange 10 which in turn is supported by the rim 7, preferably of sheet metal. The inner side wall of the channel 9 is outwardly inclined at 11.

The lower flange 12 of the rim member, which is of inwardly facing channel section, is upwardly curved in the preferred embodiment and of such dimensions as to embrace the channel 9 of the end member, the edge 13 of the flange 12 being engaged in the angle resulting from the formation of the channel in the bottom. The upper flange 14 engages the ledge 6 and when the parts are thus in engagement the bottom is securely locked to the side wall and the side wall is effectively retained in its expanded position within the channel 9.

In assembling, the rim 7 is assembled with the bottom 8 as shown in Figs. 3 and 4 and the side wall is opened or set up into general circular form as indicated in Fig. 4, and then moved downwardly until its lower edge 15 comes into engagement with the inclined side wall 11 of the bottom channel. A continued downward thrust on the side wall will force it to the bottom of the channel and expand it to bring its supporting ledge 6 under the flange 14 of the rim as shown in Fig. 2. In this completely assembled position, the side wall is securely retained in its erected or cylindrical form or position and the end member and side wall are effectively secured together. The joint between these parts is sufficiently tight to enable the use of the package as a container for products such as ice cream or the like.

The cover 16 is provided with a flange 17 having a reinforce band 18 thereon. This cover flange is adapted to telescope with the reinforcing member 4. While I have illustrated my invention as embodied in the bottom of the container, it will be understood that the same features could be employed in either end of the container.

In the embodiment of my invention shown in Fig. 6, the rim 19 is slightly modified in that the flange 26 thereof is corrugated. While it is conformed to engage the bottom portion of the bottom channel, it is not conformed to supportingly engage the inner wall of the bottom channel as is the case with the embodiment previously described.

In Fig. 7 the container side walls are made up of telescoping sections 21 and 22, which adapts the container for different volumes; further, when used as an ice cream container it can be collapsed as the contents are removed. This is of substantial advantage as it facilitates the removal of the contents, particularly the lower portion thereof.

When formed of metal, the rim facilitates the sliding of the containers on the surface upon which they may be resting and also protects the bottom, as in ice cream factories, for example, where the floors are frequently damp or even covered with a film of water.

In Figs. 8 and 9 I illustrate a further modified embodiment of my invention which utilizes a false bottom 23 resting on the bottom 8, being slidably receivable within the container wall. In this case, bottom 8 is provided with a suitable number of apertures 24 which perform the double function of permitting access to the false bottom 23 of a suitable tool whereby to elevate the false bottom as the contents of the container are used up and which also prevent the occurrence of any possible dead air space between the false bottom 23 and bottom 8 such as would interfere with the freezing of the contents of the container. The manner of assembling the parts is obvious from the foregoing description, the false bottom 23 being inserted after the other parts are in erected position.

In Fig. 10 I disclose modified provisions for facilitating application of the cover 16 in the form of an annular reinforcing rim 25 preferably of metal. This rim encircles the hoop-like reinforce member 4 and has a lowermost turned flange 26 engaging between the member 4 and an uppermost rounded bead 27 engaging the top of the container wall. The last named bead greatly facilitates the telescoping of the cover flange 17 over the container and reinforcing rim 25.

I have illustrated and described my invention in highly practical embodiments thereof. I have not attempted to illustrate various adaptations which I contemplate as it is believed these disclosures will enable those skilled in the art to embody or adapt the same as may be desired.

Having thus described my invention what I claim as new and desire to secure by Letters Patent is:

1. A container comprising a fibrous cylindrical side wall having an external hoop-like reinforce member at the bottom thereof, the upper edge of said reinforce member providing a ledge, a bottom having a depressed upwardly facing annular side wall receiving channel terminating in an upwardly projecting flange embracing the said reinforcing member of said side wall, the inner side wall of the said bottom channel being outwardly inclined, and a rim member of inwardly facing channel cross section having its lower arm upwardly curved to embrace said channel on said bottom and disposed in supporting engagement therewith and its upper arm in retaining engagement with the said ledge, the flange on said bottom being clamped between said

reinforcing member and said rim, the outwardly inclined wall of said bottom channel acting to expand the side wall into engagement with the rim when the side wall is forced downwardly into the said bottom channel.

2. A container comprising a fibrous cylindrical side wall having an external hoop-like reinforce member at the bottom thereof, the upper edge of said reinforce member providing a ledge, a bottom having a depressed upwardly facing annular side wall receiving channel terminating in an upwardly projecting flange embracing the said reinforcing member of said side wall, and a rim member of inwardly facing channel cross section having its lower arm upwardly curved to embrace said channel on said bottom and disposed in supporting engagement therewith and its upper arm in retaining engagement with the said ledge, the flange on said bottom being clamped between said reinforcing member and said rim.

3. A container comprising a fibrous side wall having an external hoop-like reinforcing member at an end thereof providing a ledge, an end member having an annular side wall receiving channel terminating in a flange embracing the said reinforcing member of said side wall, the inner side of the said channel of said end member being outwardly inclined, and a rim of inwardly facing channel cross section having its one arm conformed to embrace said channel on said end member and disposed in supporting engagement therewith and its other arm in retaining engagement with said ledge, the flange on said end member being clamped between said reinforcing member and said rim, the outwardly inclined wall of said end member channel acting to expand the side wall into engagement with the rim when the side wall and end member are forced together.

4. A container comprising a fibrous side wall having an external hoop-like reinforcing member at an end thereof providing a ledge, an end member having an annular side wall receiving channel terminating in a flange embracing the said reinforcing member of said side wall, and a rim of inwardly facing channel cross section having its one arm conformed to embrace said channel on said end member and disposed in supporting engagement therewith and its other arm in retaining engagement with said ledge, the flange on said end member being clamped between said reinforcing member and said rim.

5. A container comprising a fibrous side wall having an external ledge, an end member having an annular side wall receiving channel terminating in a side wall embracing flange, the inner side of the said channel of said end member being outwardly inclined, and a rim of inwardly facing channel cross section having its one arm in supporting engagement with said end member and its other arm in retaining engagement with said ledge, the flange on said end member being between said side wall and said rim, the outwardly inclined wall of said end member channel acting to expand the side wall into engagement with the rim when the side wall and end member are forced together.

6. A container comprising a fibrous side wall having an external ledge, an end member having an annular side wall receiving channel terminating in a side wall embracing flange, and a rim of inwardly facing channel cross section having its one arm in supporting engagement with said end member and its other arm in retaining engage-

ment with said ledge, the flange of said end member being between said side wall and said rim.

7. A container comprising a fibrous side wall provided with an external ledge at an end thereof, an end member having a peripheral wall embracing flange, a side wall receiving channel of which said flange constitutes the outer wall, the inner wall of said channel being outwardly inclined, and a rim member of inwardly facing channel section having its inner arm engageable with said ledge and its outer arm in supporting engagement with said channel, the outwardly inclined wall of said end member channel facilitating the assembly engagement of the side wall and the end member having the rim assembled therewith.

8. A container comprising a fibrous side wall provided with an external ledge at an end thereof, an end member having a peripheral wall em-

bracing flange, a side wall receiving channel of which said flange constitutes the outer wall, and a rim member of inwardly facing channel section having its inner arm engageable with said ledge and its outer arm in supporting engagement with said channel.

9. A container comprising a fibrous side wall having an external annular ledge, an end member having an annular wall receiving channel and a flange surrounding the ledge, a rim of inwardly facing channel section and embracing the channel and ledge, and an auxiliary end member telescopingly engaging the wall above said first named end member, said first named end member having an aperture therethrough, said annular channel having an outwardly inclined wall engageable by the side wall to facilitate assembly of the container.

JAMES E. ANNEN.
